UNITED STATES PATENT OFFICE

RAYMOND H. OLLEY, OF SYRACUSE, NEW YORK, ASSIGNOR TO CROUSE-HINDS COMPANY, OF SYRACUSE, NEW YORK, A CORPORATION OF NEW YORK

LOCK FOR LAMP SOCKETS

Application filed March 19, 1928. Serial No. 262,775.

This invention relates to lamp sockets and has for its object a particularly simple and efficient means for locking a lamp base or other plug in the socket so that the lamp or plug can not be removed by an unauthorized person, which locking means is particularly simple and economical in construction and highly efficient and durable in use.

The invention consists in the novel features and in the combinations and constructions hereinafter set forth and claimed.

In describing this invention reference is had to the accompanying drawings in which like characters designate corresponding parts in all the views.

Figure 1 is a plan view of a lamp socket embodying my invention.

Figure 2 is a side elevation thereof, the body of the socket being shown as separated slightly from the base.

Figure 3 is an enlarged side elevation of the lamp socket partly in section.

Figures 4, 5, and 6 are respectively an end elevation, plan view and side elevation of the jaw or locking bolt.

Figures 7 and 8 are respectively an elevation and plan view of the operating screw.

Figure 9 is a section taken on line 9—9, Figure 1.

1 designates the lamp socket body of insulation which is mounted upon a suitable base 2 having means as screws 3 for securing it to a support. The body is formed with the usual recess 4 opening through its front face and in which the usual central and threaded sleeve terminals 5, 6 of the lamp socket are mounted.

It will be understood that the sleeve terminals and the lamp socket are threaded.

40 The body is secured to the base as by screws 7 extending through the terminals 5, 6 and threaded to the base in any well known manner.

8 is a member for locking the lamp socket base or any other plug suitable to be inserted in a lamp socket, this member being a bolt or jaw carried by the body and extending laterally into the recess 4 and through a passage in the sleeve terminal 6, this jaw or bolt having inclined teeth 9 at its ends for coacting

with the lamp socket base and holding it from retrograde turning movement.

The bolt 8 is also formed with a flange or shoulder 10 for engaging the outer face of the sleeve terminal and limiting the inward movement thereof, that is, preventing it from displacement. This bolt is usually slidably mounted upon the bottom of a second recess 11 opening through the front face of the body at one side of the recess 4, the recess having a central deeper portion or notch 12 on the bottom of which the jaw or bolt slides.

The bolt is operable from the front side of the body 1 by an operating member as a screw located in the recess 11 and arranged at an angle other than a right angle to the sliding jaw or bolt 8, it being here shown as arranged at an oblique angle and having a conical end 13 thrusting in a complementary conical socket 14 in the bolt 8.

In the illustrated embodiment of my invention, the screw threads into a bridge 15 located in the recess 11 with its ends on the bottoms of the shallower portions of the recess 11, the bridge extending across the upper end of the deeper portion or notch in which the bolt 8 is located.

In order to make the screw easily operable and operable only by an authorized person, the head 16 of the screw is formed to receive a key, it being here shown as provided with notches 17 so that a bifurcated key is required to operate the same.

In operation, after the lamp is screwed into the socket or the threaded sleeve terminal 6, the screw 11 is tightened thrusting the toothed end 9 into snug engagement with the lamp base so that it can not be turned out of the socket.

This locking means is particularly advantageous in that it consists of but a few compactly arranged and easily assembled parts and in that it is operable from the front or lamp side of the socket.

What I claim is:

A lamp socket comprising a body formed with a recess opening through its front face, a sleeve terminal mounted in the recess, a second recess located at one side of the first recess and being of less depth than the same

and also opening through the front face of the body, the recess being formed with a notch in its bottom between its ends, the notch opening into the first recess, a sliding locking bolt on the bottom of the notch and projecting into the first recess, the sleeve terminal having a passage through which the end of the locking bolt projects, a bridge mounted in the second recess and extending across said notch and an operating screw threading into the bridge and coacting with the bolt to operate the same.

5 In testimony whereof, I have hereunto signed my name, at Syracuse, in the county of Onondaga, and in the State of New York,
15 this 8th day of March, 1928.

RAYMOND H. OLLEY.
